(57) **CLAIM**

The ornamental design for an actuator for a fluid flow control component as shown and described.

DESCRIPTION

This invention was made with government support under Contract No. 2127461 awarded by The National Science Foundation. The government has certain rights in the invention.

FIG. 1 is a front perspective view of an actuator for a fluid flow control component;

FIG. 2 is a front view of the actuator of FIG. 1;

FIG. 3 is a back view of the actuator of FIG. 1;

FIG. 4 is a top view of the actuator of FIG. 1;

FIG. 5 is a bottom view of the actuator of FIG. 1;

FIG. 6 is a right side view of the actuator of FIG. 1; and,

FIG. 7 is a left side view of the actuator of FIG. 1.

The broken lines in the figures depict portions of the article which form no part of the claimed design. The short-dash/long-dash broken lines illustrate boundary lines and form no part of the claimed design.

1 Claim, 7 Drawing Sheets
